UNITED STATES PATENT OFFICE

FREDERICK O. E. EGGERT, OF CHICAGO, ILLINOIS

GYNECOLOGIC INSTRUMENT

Application filed November 6, 1930. Serial No. 493,835.

This invention relates to an improved instrument designed to facilitate the vaginal insertion and correct intra-vaginal placement of vaginal pessaries.

Among the objects of the invention are, to provide a simple instrument that will effect vaginal insertion and correct intra-vaginal application of a pessary without requiring vaginal insertion, or contact with the external genitalia, of the physician's or patient's finger or fingers, and without the need for any secondary devices or manipulations, to provide an instrument that may be readily manipulated by the patient for self-application, to provide an instrument requiring the use of but one hand, to provide an instrument that will minimize irritation and the danger of bacterial contamination, and lessen the discomfort attending the operation, to provide an instrument through which the efficiency of the use of a pessary for intra-vaginal medication may be increased, to provide an instrument that cannot cause injury to the delicate tissues with which it comes into contact, and generally, to provide an improved and highly sanitary one-piece gynecologic instrument of the character specified.

An approved mechanical embodiment of the invention is illustrated in the accompanying drawings, in which—

Fig. 1 is a top plan view of the instrument.
Fig. 2 is a side elevation.

Fig. 3 is a cross section on the line 3—3 of Fig. 1.

Fig. 4 is a perspective view of a pessary.

Fig. 5 is a perspective view illustrating the manner in which the pessary is mounted and stretched on the instrument preliminary to its application.

Referring to the drawings, Fig. 4 illustrates a common form of pessary designed to be serviced by the present instrument, the same consisting of a substantially hemispherical shell A of thin rubber, the edge portion of

which is wrapped and sealed around a ring of fine spiral wire to form a flexible rim or bead B. In the smaller sizes of pessary, this bead B encircles the cervix uteri, while in the larger sizes, such as that illustrated, the application is somewhat different, the bead

B being at one point thereof hooked over the cervix and the remaining portion thereof lying against the wall of the vagina.

The instrument forming the subject matter of the present invention is a one-piece device consisting essentially of a bar, preferably of a light metal such as aluminum or an aluminum-chromium alloy, specially shaped, as hereinafter described, to serve as a carrying and stretching tool for the pessary when applying the latter, and having a smooth and highly polished surface to prevent injury to the tissues with which it comes in contact. This bar comprises what I term a body portion 10 and a handle portion 11 continuous with the body portion and preferably extending downwardly at a low angle to the latter in the horizontal position of the body portion 10, as shown in Fig. 2. The body portion 10 is preferably tapered widthwise, as shown in Fig. 1, being gradually narrowed from its junction with the handle portion to its forward end; and, as shown in Fig. 2, it is also preferably of gradually increased thickness from its junction with the handle portion to its forward end. In the forward end of the bar is a transverse notch 12 suitably shaped to engage with the rim or bead B of the pessary, as shown in Fig. 5. The rear end of the handle portion 11 is also preferably formed with a notch 13 that, in manipulating the device, forms a seat or rest for the little finger of the hand, as shown.

In the upper surface of the bar there is also preferably formed a shallow longitudinal groove or channel 14 lying partly in the body portion 10 and partly in the handle portion 11, which groove serves as a thumb guide when stretching and elongating the pessary, preventing the tip of the thumb from slipping off the bar sidewise during the stretching or depositing operations, as clearly shown in Fig. 5.

In the use of the instrument, the body portion 10 is laid diametrically across the convex side of the pessary with its upper or grooved side in contact with and depressing the hemispherical body A of the pessary, and the notch 12 is engaged with the rim or bead

B. The thumb then engages with the rim or bead at a diametrically opposite point over the channel 14, the tip of the thumb entering and being guided by the channel. The little finger is also engaged with the notch 13 at the rear end of the handle, and the thumb is then moved downwardly along the channel 14, stretching and narrowing the pessary, as shown in Fig. 5. The little finger anchorage afforded by the notch or seat 13 greatly facilitates the stretching operation by preventing the rest of the hand from slipping upwardly on the tool and thus enables a strong downward pull to be exerted by the thumb. The loaded instrument is then inserted into the vaginal canal until its notched tip passes behind the cervix, depositing the upper end of the stretched rim or bead B at that point, and the instrument is then withdrawn, whereupon the deposited pessary resumes its original round form, with the remaining portion of the rim or bead lying against the wall of the vagina and thus closing the mouth of the uterus, so that a vaginal or uterine medicament previously deposited in the pessary is not wasted and readily finds its way to its designed point of application.

From the foregoing it will be apparent how the described instrument effects the stated purposes and objects thereof; its principal advantages being that it can be manipulated by the patient in privacy without requiring the services of a physician or surgeon; that it eliminates all contact of the fingers with internal parts and organs, thus conducing to cleanliness and lessening the liability to infection; and that it saves the time and patience usually required of the physician in instructing the patient. And while I have shown and described one useful and practical form or embodiment of the invention, it is manifest that the detail features thereof may be variously modified without involving any departure from the principle, or sacrificing any of the advantages, thereof. Hence I do not limit the invention to the specific form shown and described, but reserve all such variations and modifications as fall within the spirit and purview of the appended claims.

I claim:

1. A one-piece gynecologic instrument of the character described, consisting of a bar comprising a body portion adapted to underlie and support a pessary and formed with a notched forward end to engage with the rim of the pessary, and a handle portion continuous endwise with said body portion, said bar formed in its upper surface with a shallow longitudinal groove constituting a thumb guide, and at the rear end of its handle portion with a transverse notch constituting a finger rest to facilitate the stretching of the pessary by the thumb.

2. A one-piece gynecologic instrument of

the character described, consisting of a bar comprising a body portion adapted to underlie and support a pessary and formed with a notched forward end to engage with the rim of the pessary, and a handle portion continuous endwise with, and inclined downwardly at a low angle from, said body portion, said bar formed in its upper surface with a shallow thumb guiding groove formed partly in said body portion and partly in said handle portion constituting a thumb guide, and at the rear end of its handle portion with a transverse notch constituting a rest for the little finger of the hand to facilitate the stretching of the pessary by the thumb.

3. A one-piece gynecologic instrument of the character described, consisting of a bar comprising a body portion of gradually decreased width and increased thickness from its rear end to its forward end adapted to underlie and support a pessary and formed with a notch in its forward end to engage with the rim of the pessary, and a handle portion continuous endwise with, and inclined downwardly at a low angle from, said body portion, said bar formed in its upper surface with a shallow thumb guiding groove formed partly in said body portion and partly in said handle portion constituting a thumb guide, and across the rear end of its handle portion with a transverse notch constituting a rest for the little finger of the hand to facilitate the stretching of the pessary by the thumb.
